UNITED STATES PATENT OFFICE.

JAMES M. DAYTON, OF TORRINGTON, CONNECTICUT, ASSIGNOR TO EXCELSIOR NEEDLE COMPANY, OF TORRINGTON, CONNECTICUT, A CORPORATION OF CONNECTICUT.

CARBURETER.

1,016,251.

Specification of Letters Patent.

Patented Feb. 6, 1912.

Application filed November 2, 1909. Serial No. 525,942.

To all whom it may concern:

Be it known that I, JAMES M. DAYTON, a citizen of the United States, residing at Torrington, in the county of Litchfield, State of Connecticut, have invented certain new and useful Improvements in Carbureters, of which the following is a description, reference being had to the accompanying drawing and to the figures of reference marked

10 thereon.

The invention relates to new and useful improvements in carbureters, and more especially to the general arrangement of the valves for controlling the supply to the float chamber, and the valve for controlling the supply to the mixing chamber; also the relation of these parts to the float chamber and also to the construction of the float chamber.

An object of the invention is to provide a durable means for connecting the float to the valve stem and to generally improve the arrangement of parts and the efficiency of the carbureter.

In the drawings which show by way of illustration one embodiment of the invention,--Figure 1 is a sectional view through the carbureter with my improvements applied thereto; Fig. 2 is a section on the line 2--2 of Fig. 1; Fig. 3 is a detail of the lower part of the main casing, with the bowl forming the float chamber removed; and Fig. 4 is a detail in cross section of the float, showing its connection to the supply valve.

My improved carbureter comprises a main casing 1, which as herein shown is cast in a single piece and has a main air opening 2, an auxiliary air inlet opening 3, and an outlet 4 leading to the motor, which is controlled by a throttle valve 5 of the usual

40 construction.

The auxiliary air inlet opening 3 is controlled by a valve 6 attached to a valve rod 7, which in turn is controlled by a spring mounted in a supporting casing 8, carried by 45 the main casing 1 of the carbureter. This auxiliary air inlet valve and its controlling mechanism form no part of the present invention, but are shown, described and claimed in my application filed of even date 50 herewith, Serial Number 525,941.

The main casing 1 between the main air inlet 2 and the auxiliary air inlet, is deflect- ed downwardly, forming a U-shaped pas-

sage 9, through which the air is drawn by the suction of the engine. At the lower portion of the U-shaped passage 9 is an upwardly projecting nozzle 10, which supplies the gasoline or other liquid fuel to the carbureter. Said nozzle is controlled by the needle valve 11 mounted in suitable bearings formed in the main casing 1. The main casing 1 below the nozzle 10 has a downwardly projecting sleeve 12 formed with a shoulder 13. The main casing 1 is also provided with a laterally projecting disk 14, which forms the cover or top of the float chamber.

A bowl 15 which is preferably of spun brass, has a central opening which fits on to the sleeve 12, so that the said bowl rests 70 against the flange 13. When the bowl is seated against the flange 13, the upper edge thereof engages the disk or top 14, so that the chamber is tightly closed. A nut 16 threaded on the sleeve 12, serves to hold the 75 bowl in its proper position.

A float 17 is arranged within the float chamber, formed by the bowl 15, and said float may be of any desired construction. As herein shown, said float is provided with 80 a central opening, which surrounds the sleeve 12, and which is considerably larger in diameter than said sleeve. At the lower edge of the central opening through the float is an inwardly projecting flange 18. 85 The sleeve 12 has a cut away portion or recess 19, which extends transversely through the sleeve, opening at each end into the float chamber. Said sleeve also has a vertical opening 20 extending from the recess 19 90 downwardly. The sleeve 12 at its lower end is connected with the gasoline or liquid fuel supply, and the fuel passes through the opening 20 and the recess 19 into the float chamber.

As a means for controlling the supply of gasoline or liquid fuel, I have provided a valve 21 which engages a valve seat 22 formed in the sleeve 12 by contracting the opening 20 leading centrally therethrough. 100 The stem 23 is, of course, slightly smaller than the opening 20 at the point where said valve stem extends through the same, and said valve stem extends upwardly across the recess 19 into a guiding way in the upper 105 portion of the sleeve 12. Said valve stem 23

intermediate its ends is threaded into a boss 24, which may be formed integral with the cross bar 25. Said cross bar 25 extends through the recess 19, and is bolted or secured in any other desirable way to the flange 18 on the float 17. It will readily be seen that as the float 17 moves up and down, the valve 20 will be raised and lowered through the connection between the valve 10 stem and the cross bar attached to the float. When it is desired to adjust the valve so as to vary the amount of fuel normally contained in the float chamber, the supply coupling for the carbureter is released from the 15 threaded sleeve 12, and the lower end of the valve 22 has a transverse slot to receive a screw driver or other similar implement, so that said valve stem may be turned, and by reason of its thread connection with the 20 float, said valve stem may be turned into or out of said threaded boss, thus changing the relative position of the valve and the float. The threaded boss may be split either horizontally or vertically, and will serve as a 25 friction means for preventing accidental turning of the valve stem relative to the float. When it is desired to increase the frictional grip of the boss, the parts may be slightly pressed together, so as to change the 30 normal inclination of the parts of said boss relative to each other, and thus increase the frictional grip of the same on the valve stem. It will thus be seen that I have provided a 35 ready means for adjusting the supply valve, without in any way disturbing the assembled carbureter.

In order that the float chamber may be readily accessible for inspection, I have provided said chamber with an opening 26, 40 which is formed in the top or cover 14. Said opening may be closed in any suitable way, and, as herein shown, I have provided a screw cap which may be readily removed in order that access to the chamber may be 45 had. If it is desired to flood the chamber at any time, all that is necessary is to remove the cap, and by inserting the finger the float may be depressed and the chamber flooded. 50 It is essential to determine with certainty the normal height of the liquid in the float chamber, and to ascertain if from any cause the fluid level is above or below the normal height. In order that this may be readily 55 determined, I have provided a gage pin 27, which as herein shown is secured to the main casing of the carbureter at a point as near the supply nozzle of the carbureter as possible. Said gage pin projects into the float 60 chamber, and may be made of celluloid, if desired, so that it may be readily seen when the screw cap 26 is removed. By placing the gage pin as near as possible to the fuel nozzle, the proper level of the liquid fuel 65 may be determined, although the carbureter

by reason of its attachment to a machine may be tilted out of normal position. The fuel passes from the float chamber through an inclined opening 28 formed in the main casing, which opening leads to the nozzle 10. 70

A draining hole 32 is formed longitudinally through the sleeve 12, and extends into the lower portion of the V-shaped passage in the main casing. An outlet hole 33 extends from the hole 32 to the outer surface of the sleeve, preferably at a point just below the nut 16. The lower end of the hole 32 will be closed by the connection to the supply pipe. This hole and outlet serve for draining excess liquid fuel from the 80 mixing chamber, should the valve fail to seat.

Having thus particularly described my invention, what I claim as new and desire to secure by Letters Patent, is: 85

1. A carbureter including in combination, a main casing having an air passage therethrough, a downwardly projecting sleeve carried by said main casing having an opening extending centrally through the sleeve, 90 a float chamber surrounding said sleeve, a valve for controlling the fuel supplied to the float chamber, said valve having a stem sliding in the opening in said sleeve, a fuel-delivering nozzle directly above said sleeve 95 and projecting into said air passage, said sleeve having an opening leading from the central opening to the float chamber, and a needle valve for controlling the supply from said nozzle. 100

2. A carbureter including in combination, a main casing having a U-shaped air passage, a downwardly projecting sleeve carried by said main casing and having an opening extending therethrough, a float 105 chamber connected to said sleeve and surrounding the same, a valve for controlling the fuel supplied to the float chamber, said valve having a stem sliding in the opening in said sleeve, a fuel-delivering nozzle directly above said sleeve and projecting into said U-shaped air passage, said sleeve having an inclined opening extending from said central opening to the float chamber and connecting with said central opening adjacent the nozzle, and a needle valve for controlling the supply from said nozzle. 110

3. A carbureter including in combination a main casing having an air passage therethrough, a downwardly projecting sleeve, a supply valve located in said sleeve, a float surrounding said sleeve, said sleeve having a transverse opening therethrough, across which the stem of the valve extends, a cross bar extending through said opening and attached to said float, said cross bar having a threaded connection with the stem of said valve and a fuel delivering nozzle in line with said sleeve and projecting into said air passage, said fuel delivering nozzle and 120

said sleeve having an opening leading to the float chamber.

4. A carbureter including in combination, a main casing having an air passage therethrough; a downwardly projecting sleeve, a supply valve located in said sleeve, a float surrounding said sleeve, said sleeve having a transverse opening therethrough, across which the stem of the valve extends, a cross bar extending through said opening and attached to said float, a threaded boss formed on said cross bar into which the stem of the valve is threaded and a fuel delivering nozzle in line with said sleeve and projecting into said air passage, said fuel delivering nozzle and said sleeve having an opening leading to the float chamber.

5. A carbureter including in combination, a main casing having an air passage therethrough, a float chamber, a fuel nozzle having a passage leading to said float chamber, a float having a central opening therethrough, an inwardly projecting flange carried by said float, a cross bar secured to said flange, a horizontally split nut mounted on the cross bar, a valve for controlling the supply to the float chamber, the stem of said valve being threaded into said split nut,

whereby the same may be adjusted and frictionally held in adjusted position.

6. A carbureter including in combination, a main casing having a U-shaped portion through which the air passes, a downwardly projecting sleeve formed in said casing at the lower portion of said U-shaped part, said sleeve having a central opening therethrough, and a transverse opening leading from said central opening into the float chamber, a bowl secured to said sleeve, a cover for the bowl secured to said casing, a float located in said bowl, a valve located in the opening in said sleeve, and connected to said float, an upwardly projecting nozzle formed in said air passage at the lower portion of said U-shaped part, said sleeve having an inclined opening for connecting said nozzle to said float chamber, and a needle valve for controlling the supply of fuel from said nozzle.

In testimony whereof I affix my signature, in presence of two witnesses.
